United States Patent

Des. 237,756
Patented Nov. 18, 1975

237,756

STREET ADDRESS DISPLAY SIGN

Richard J. Williamson, 218 Northhill Drive,
San Antonio, Tex. 78201

Filed May 18, 1972, Ser. No. 254,835

Term of patent 14 years

Int. Cl. D20—03

U.S. Cl. D96—12 F

FIG. 1

FIG. 2

FIG. 1 is an exploded view of the street address display sign showing my new design.

FIG. 2 is a fragmentary view of a second embodiment of my design, the post and sign being omitted for convenience of illustration.

The numerals are shown in broken lines in FIG. 1 for illustrative purposes only. The second embodiment differs from the first only in the base configuration. The sign in FIG. 1 is shaded to indicate contrast.

The back side of the sign is identical to the front side except that the numerals run from the outside toward the post so that they can be read when viewed from the reverse side.

I claim:

The ornamental design for a street address display sign, as shown and described.
